UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

OIL CUP.

Application filed July 27, 1921. Serial No. 487,955.

To all whom it may concern:

Be it known that I, WILLIAM J. FRISBIE, a citizen of the United States, and a resident of Chicago, in the county of Cook and State 5 of Illinois, have invented certain new and useful improvements in Oil Cups, of which the following is a specification.

My invention relates to oil cups, and covers particularly improved means for strengthening 10 the inlet end of the cup and for supporting a cover for the cup.

The important object of the invention is to provide a belt around the cup adjacent to its mouth to strengthen the cup against bending and to accurately support a cover. The belt is preferably continuous and formed of 15 a single piece of sheet metal, the metal during the process of formation of the belt being folded together at two spaced apart points 20 to form extensions with double wall thickness to provide hinge pin supports and guides for the cover. Being of a single piece, the belt can be accurately applied and held in place on the cup while it is being 25 soldered into place.

On the accompanying drawing I show a cup embodying the features of my invention. On this drawing

Fig. 1 is a side elevational view,

Fig. 2 is a rear elevational view,

Fig. 3 is an enlarged sectional view on plane 3—3 Fig. 1,

Fig. 4 is an enlarged sectional view of the upper end of the cup on plane 4—4 Fig. 2,

Fig. 5 shows an annular plate of metal from which the belt is formed,

Fig. 6 shows the plate after being turned up to cylindrical form, and

Fig. 7 shows a modified form of belt.

The cup shown is formed integral of 40 sheet metal and comprises the cylindrical body part 10 and the reduced threaded end or nipple 11. The upper section 12 of the part 10 is of reduced diameter to 45 form the annular external shoulder 13 and to receive my improved strengthening and cover supporting belt or band 14. The belt is circular and dimensioned to be applied with a sliding fit on the cup and has 50 the spaced apart arms 15 and 16 extending laterally therefrom to support the hinge pin 17 for the cover 18. The cover has the depending ears 19 and 20 which engage against the outer sides of the arms and receive the hinge pin. The cover is accurately 55

guided by the ears to accurately and snugly fit against the upper edges of the cup section 12 and the band 14. The cover has also the short peripheral flange 21 for engaging along the sides of the cup, and has the lip 22 60 diametrically opposite the hinged connection, said lip serving as a finger hold whereby the cover may be readily opened against the force of the coil spring 23 which encircles the hinge pin and has one end engaging 65 against the cup body and the other end against the rear edge of the cover. The walls of the extensions 15 and 16 are in intimate contact so that double thickness support is provided for the hinge pin. 70

The strengthening and cover supporting belt is preferably formed from a flat sheet metal blank of annular form as shown in Figure 5. This blank is stamped from a stock sheet and is then turned to form a 75 cylindrical band as shown in Figure 6. At suitable spaced apart points sections of this band are then folded together into intimate engagement to form the hinge pin supporting extension 15 and 16. The finished 80 belt is of a diameter to be slid snugly on to the section 12 and when in place the band intimately engages the cylindrical section 12 throughout its entire extent as clearly shown in Figure 3. After 85 being slipped on to the cup solder is applied to permanently securely hold the belt in place. By looping and folding sections of the cylindrical band the extensions 15 and 16 will be of double thickness 90 and exceedingly strong. The belt being continuous (as distinguished from a split belt) possesses great strength and will not spread when applied to the cup but will accurately hold its position thereon during the 95 soldering operation. The belt is of a width to engage securely on the shoulder 13 of the cup and to terminate at its upper edge flush with the upper edge of the cup, this providing an annular seat for the cover of double 100 thickness which will prevent entrance of the weather and of dust and dirt, the cup section 12 is of sufficiently reduced diameter so that the belt when applied will have its outer surface flush with the outer surface of 105 the cup body below the section 12.

The double thickness of wall around the mouth of the cup makes the cup structure extremely rigid and prevents bending or denting of the cup and the cup will always pre- 110

sent a true seat for the cover. The lower part of the cup body has the knurled or roughened surface 24 which affords a good grip whereby the cup may be more readily 5 screwed into its support. The nipple 11 has the outlet opening 25 for the cup contents.

The belt could be made of a single piece of metal ribbon as shown in Figure 7, the ends 26 and 27 of the ribbon being brought intimately together to form one of the cover 10 supporting projections.

Having described my invention, I claim as follows:

1. In an oil cup, the combination of a body 15 part for containing oil, a belt surrounding the exterior of said body part adjacent to its entrance edge and extending around its entire circumference, sections of said belt being folded intimately together to form double 20 thickness parallel lateral extensions, and a cover for the cup hinged to said extensions.
2. In an oil cup, the combination of a

body part for containing oil, a strengthening and supporting belt in the form of a close annular endless band of sheet metal, 25 said band intimately fitting entirely around said body part adjacent its edge, sections of said band being looped to form two double thickness laterally extending arms, and a 30 cover for the cup hinged to said arm.

3. In an oil cup, the combination of a cylindrical body part for containing oil, the upper section of said body part being contracted, a belt surrounding said contracted section with its upper edge flush with 35 the edge of the body part, said belt being in the form of an endless metal band having sections folded intimately together to form two double walled parallel extensions, and a cover for the cup hinged to said extensions. 40

In witness whereof, I hereunto subscribe my name this 22nd day of July A. D., 1921.

WILLIAM J. FRISBIE.
